(57) **CLAIM**

The ornamental design for display screen or portion thereof with transitional graphical user interface, as shown and described.

DESCRIPTION

FIG. 1 is a front view of the first image in a sequence of a display screen or portion thereof with transitional graphical user interface, showing our new design;

FIG. 2 is a front view of the second image thereof;

FIG. 3 is a front view of the third image thereof;

FIG. 4 is a front view of the fourth image thereof;

FIG. 5 is a front view of the fifth image thereof; and,
FIG. 6 is a front view of the sixth image thereof.

The appearance of the transitional graphical user interface sequentially transitions between the images shown in FIGS.

1-6. The process or period in which one image transitions to another forms no part of the claimed design.

The broken lines showing a device, display screen, and portions of the graphical user interface form no part of the claimed design.

1 Claim, 6 Drawing Sheets
